(57) **CLAIM**

The ornamental design for a squeegee, as shown and described.

DESCRIPTION

FIG. 1 is a perspective view of a squeegee in accordance with the present invention;

FIG. 2 is a top view of the squeegee; and,

FIG. 3 is a perspective bottom view of the squeegee.

The broken lines are for environmental purposes, and do not form part of the claimed design.

1 Claim, 3 Drawing Sheets

FIG. 1

FIG. 2

FIG. 3
